CLAIM

The ornamental design for a terminal adapter, as shown and described.

DESCRIPTION

FIG. 1 is a front elevational view of my new terminal adapter;

FIG. 2 is a top plan view thereof;

FIG. 3 is a left side elevational view thereof;

FIG. 4 is a right side elevational view thereof; and,

FIG. 5 is a back elevational view thereof.

The adapter as seen from the bottom forms no part of the claimed design.
